**HOUSING FOR A COMBINED RADIO AND
CALENDAR OR SIMILAR ARTICLE**

Akira Katoh, Tokyo, Japan, assignor to
General Electric Company

Filed June 21, 1971, Ser. No. 155,411

Term of patent 14 years

Int. Cl. D14—03

U.S. Cl. D56—4 B

FIG.1

FIG.2

FIG.3

FIG.4

FIG.5

FIG.6

FIG. 1 is a front elevational view of a housing for a combined radio and calendar or similar article, showing my new design;

FIG. 2 is a rear elevational view;

FIG. 3 is a top plan view;

FIG. 4 is a left side elevational view;

FIG. 5 is a right side elevational view; and

FIG. 6 is a bottom plan view thereof.

Portions of the drawing figures are stippled to indicate contrast in appearance, the stippling being continuous within the boundaries indicated.

I claim:

The ornamental design for a housing for a combined radio and calendar or similar article, as shown and described.
